UNITED STATES PATENT OFFICE.

WEBSTER LEE WARD, OF MOHAWK, TENNESSEE, ASSIGNOR TO CURTIS-WARD COMPANY, OF CHICAGO, ILLINOIS, A CORPORATION OF ILLINOIS.

PORTABLE TURN-TABLE.

1,123,825.

Specification of Letters Patent.

Patented Jan. 5, 1915.

Application filed October 28, 1914. Serial No. 869,020.

To all whom it may concern:

Be it known that I, WEBSTER LEE WARD, a citizen of the United States, residing at Mohawk, in the county of Greene, State of Tennessee, have invented a new and useful Portable Turn-Table, of which the following is a specification.

My invention relates to portable turn-tables and particularly to turn-tables designed and adapted for use in connection with construction work and road building.

The object of the invention is to provide a turn-table readily and easily transportable on soft earth and ordinary road beds without the necessity for building permanent and expensive tracks or floors.

A further object is to provide a portable turn-table whereon heavy motor trucks, used in construction work and road building, may be turned within their own length at the point of use facilitating such work by reducing the time necessary to travel to a point where such truck could ordinarily be turned; also avoid traveling over the portion of the road already constructed.

A further object is to provide such a turn-table as can be moved from place to place by the power of the motor or other trucks and vehicles which it is designed to turn.

Another object is to provide a turn-table so simple in construction as to be capable of assemblage by any ordinary workman and having so few parts so arranged as to be durable as well as simple in construction and economical in cost of building. The entire turn-table may be made of metal if desired.

The special and novel phase of the invention here disclosed will be better understood from reference to the following detailed description which is to be taken in conjunction with the accompanying drawings, wherein—

Figure 1 is a plan view of my portable turn-table illustrating the structure in the position and as assembled for use. Fig. 2 is a side elevation of same, showing the approaches to the structure proper and the curved ends of the skids which support and render mobile the entire structure. Fig. 3 is a vertical transverse section taken upon the plane indicated by line A—A in Fig. 1. Fig. 4 is a transverse horizontal section taken on line B—B of Fig. 3. Fig. 5 is

a detailed view of one of the four wheel members arranged on the I-beams at each side of the pivot I beam as shown in Fig. 1. Fig. 6 is a detailed view of the wheel members arranged intermediate of and parallel with the skids. Fig. 7 is a detailed view of the four corner wheel members which are located between the wheels shown in detail in Figs. 5 and 6. Fig. 8 is a detailed view of the means for fastening the I beams to the skids.

The illustrated embodiment of my invention, which although consisting of few parts, easily assembled, comprises three main members,—the base, support or skids 1—1 with the I beams 2 placed thereon and fastened thereto and the wheels 3 arranged on the I beams as shown in Fig. 1; the circular track comprising two semi-circular T irons so placed as to form a complete circle and supported upon the wheel 3; and the track 5—5 with the approaches thereto at both ends 6—6, the track being supported and carried by the circular track 4.

In carrying out the invention and in practice I first provide the skids 1—1 preferably of channel iron, curved up at both ends, the length of the skids preferably being the same as the length of the tracks 5—5 although they may extend beyond so long as they do not interfere with the positioning of the approaches 6 as best shown in Fig. 2. It is desirable to have the skids or runners of sufficient width so that the entire structure will not cut too deeply into the soft earth or road bed thus facilitating transportation. These skids or runners 1—1 might also be made of wood if desired and when so made should be sheathed with a metal strip extending over the curved ends. Each end of the skids 1—1 should be provided with holes 7 for attaching a chain or tongue or other suitable means for connecting the power used in moving the entire structure from place to place. Upon the skids 1—1 I next position the I beams 2 best shown in Fig. 1 preferably five in number although a greater number can be used if desired. These I beams must be so distanced and arranged as to support the wheels in the proper places to conform to the circular track 4 as shown in Fig. 1, the best results being obtained in the operation of the circular track by having the number

of wheels 3 arranged as shown in Fig. 1, the particular arrangement of the wheels being more specifically described herein-after. In practice I have found the arrangement shown in Fig. 8 satisfactory as means for fastening the I beams 2 to the skids 1-1 although I do not wish to be limited to that method of fastening. The fastening means as shown in Fig. 8 are 10 preferably riveted to the I beams 2 by means of rivets 9 so that there will be few small parts in shipment obviating the danger of losing them or difficulty in assembling and provided with holes so that they may 15 be bolted to the skids by means of bolts 10.

The two wheels on the pivot I beam are arranged and attached as shown in Figs. 3 and 4, Fig. 3 showing a vertical sectional view of the fastening means and Fig. 4 20 showing a horizontal sectional view of the same fastening means. The axle member 11 is so shaped that the circular wheel slips over it and is retained in position by a pin 12. At the back of the wheel the axle is 25 provided with a shoulder 13 so that the wheel is maintained in fixed position. Beginning from the shoulder the spindle is shaped so that it fits over and registers with the I beam and is fastened thereto by means 30 of bolts or rivets 14 as shown in Figs. 3 and 4. All of the wheels 3 as used in my invention have a flange or projection on the inner side so that the circular track 4 will travel thereon in a definite, fixed position. These wheels are, in practice, necessarily 35 large enough so that they will support the load and permit the circular track to be turned quickly and easily.

The wheels to be carried by the I beams 40 immediately at either side of the pivot I beam are placed and fastened to those I beams as shown in Fig. 5 being different from the arrangement shown in Fig. 4 only in that the axle is longer and bent so as to 45 conform to the circular track 4. The two wheels supported at the center of the outermost I beams are placed and fastened as shown in Fig. 6, the arrangement of the wheel on the axle being as previously explained in regard to Fig. 4. The axle however is shorter and terminates at the back in the plate 15 which fits against the I beam and is fastened thereto by means of 50 bolts or rivets 16. The wheels arranged at 55 each end of the outermost I beams are fastened thereto substantially as shown in Fig. 7, the support for these wheels being fastened to the skids 1-1 and having two upright members 17-17, the axle of the wheel 60 fitting into the uprights on either side and held in place by means of the pins 18-18.

The circular track 4 is preferably made of two pieces of T iron each bent to make a half circle so that when the two are brought 65 together and fastened by any suitable

means they form a circle, of required size. This circular track rests upon and registers with the location of the wheels as already described so that the circular track is held in place without engaging the flange or inner projection of the wheels. Upon the circular track are arranged two tracks 5-5 70 of channel iron of sufficient width to accommodate the wheel of any motor or other truck or vehicle, curved outwardly at the ends as shown at 20 so that the wheels will not strike a sharp corner and be injured in driving on to the turn-table. Tracks 5-5 are provided at both the outer and inner edge with flanges to prevent the vehicle 75 from slipping off; the inner edges have provided an additional angle iron into which planking 21 fits; it is necessary in practice to use this planking between tracks 5-5 so that ordinary road traffic can pass over the 80 turn-table. This flooring 21 can be made of plain or corrugated sheet metal in one or more pieces so that the entire structure can be made of metal if desired. The tracks 85 5-5 are fastened to the circular track 4 by 90 means of countersunk bolts 22.

Between the tracks 5-5 is placed a brace 95 of channel iron 23 fastened to the under side of the tracks 5 by means of countersunk bolts 24 and is designed to give rigidity to the entire structure, to maintain the tracks in their proper position and to insure the perfect operation of the circular track 4. This channel bar 23 is designed to receive the king bolt 25 as shown in Fig. 3, the 100 king bolt being countersunk as there shown and placed directly in the center of the circle formed by the circular track so that perfect balance and concentricity will be maintained at all times.

In using the above described structure for turning motor and other trucks and vehicles, it is necessary to have approaches 6-6 so placed as shown in Fig. 2 as to permit the truck to be run on to the track of turntable 105 in balance so that circular track of turntable may be turned about by means of levers 26. When the truck has been turned by means of the turn-table to the position desired for dumping the load, it will then be 110 facing so that it can be driven directly off the turn-table in the same direction from whence it came.

By means of the above described structure it will be seen that a turn-table has 115 been provided which may be moved from place to place in road building by the power and means ordinarily and usually there available with perfect ease and without building any floor or tracks and at the same time be capable of use as a turn-table at any place and in any position and upon any character of support, it usually resting 120 merely upon the earth of the road bed.

While I have herein disclosed one embodiment

ment of the present invention I am aware that changes in detail may be made without deviating from the spirit thereof and I desire that the protection here sought should

5 include such changes and modifications in detail as reasonably may be made within the terms of the appended claims.

Having fully described my invention what I claim and desire to secure by Letters

10 Patent is:

1. In a turn-table the combination of a frame, a pair of runners for carrying said frame, a circular track rotatably mounted on said frame and a vehicle support on said 15 circular track.

2. In a turn-table the combination of a frame, a pair of runners for carrying said frame, a circular track rotatably mounted on said frame and a vehicle support movable with said circular track.

3. In a turn-table the combination of a frame, a pair of runners for carrying said frame, a plurality of rollers, a circular track rotatably mounted on said frame and adapted 25 to be carried by said rollers and a vehicle support movable with said circular track.

4. In a portable turn-table the combination of a frame, parallel runners for carrying said frame, bars mounted thereon pro-

vided with rollers, a circular track rotatably mounted on said frame and adapted to be carried on said rollers for the purpose set forth.

5. A turn-table comprising a frame having 35 parallel skids, bars provided with rollers mounted thereon, a circular track rotatably mounted on said frame and carried by said rollers, tracks mounted on said circular track, approaches to the tracks substantially as and for the purpose set forth.

6. In a turn-table the combination of two parallel bars forming skids or runners rendering the entire structure mobile, bars mounted thereon provided with wheels upon 45 which are supported and carried a complete rotatable circular track, parallel track members mounted upon said circular track and secured thereto, means for securing their respective parts in place and together, 50 approaches to the tracks, levers for turning the circular track and a central pivot as described and shown.

In witness whereof, I hereunto subscribe my name to this specification in the presence of two witnesses.

WEBSTER LEE WARD.
